UNITED STATES PATENT OFFICE.

FRANK HENRY RUSS, OF NEW YORK, N. Y.

FOOTSTEP-CORRECTOR.

1,118,058.

Specification of Letters Patent.

Patented Nov. 24, 1914.

Application filed May 25, 1914. Serial No. 840,936.

To all whom it may concern:

Be it known that I, FRANK HENRY RUSS, a citizen of the United States, and a resident of New York, borough of Brooklyn, in the county of Kings and State of New York, have invented certain new and useful Improvements in Footstep-Correctors, of which the following is a specification.

My invention relates to improvements in 10 footwear; and is particularly designed both to prevent and to cure the deformity due to the falling or breaking down of the arch comprising the bones in the human foot between the ball and the heel of the same.

15 As I shall set forth fully hereinafter, I have found by study and experiment that much of the troubles with the feet experienced by civilized, shoe-wearing people is due to the habit, incurred by nearly every 20 individual, of walking with the feet not parallel, but with the toes everted or pointing outward instead. This mode of locomotion subjects the bones in the arch of the foot to unduly great stresses; and thus 25 may soon produce the deformity above mentioned.

It is the primary object of my invention to eliminate these unnatural stresses; and I attain my end by a construction which automatically 30 compels people using it, effectively though unconsciously to get into the habit of making their footsteps correctly; thus obviating the "out-toeing" evil.

The above and other objects and advantages of my invention will appear from the 35 following specification, taken in connection with the accompanying drawings; which illustrate one or more embodiments of my inventive idea; the same characters of reference being employed to indicate the same parts throughout the several views. On said drawings

Figure 1 is a bottom plan of one form of my invention, showing it applied to the heel 40 of a shoe for the left foot; Fig. 2 is a side view, showing my invention applied to a shoe intended for the right foot; the outer side of the same being presented to the observer; Fig. 3 is a view similar to Fig. 2, 45 showing the heel of the shoe partly broken away; and in section on line 3—3, Fig. 1. Fig. 4, like Fig. 1, is a bottom plan, but 50 showing a modified form of my invention; the heel being the left heel, as before; and

Fig. 5 is a section taken on the line 5—5 of Fig. 4.

I wish to state at the outset that by observing how large a proportion of civilized people, accustomed to wearing shoes, suffer from misplaced bones in the arches or insteps of their feet; and that uncivilized people not in the habit of wearing shoes rarely ever suffer such discomforts; I was led to an investigation to determine the cause of such troubles. First I discovered 60 that shoeless races invariably walk with their feet parallel to each other; the toes pointing straight ahead; while shoe-wearing races generally walk with their toes everted or turned more or less outward 65 from parallel position. I then concluded that a careful examination of the anatomy of the foot, and the difference in the effects on the arch thereof produced by walking with the toes everted or turned outward; 70 and by walking with the toes parallel, would reveal the chief causes of fallen and deformed arches. My conclusion was correct, as proven below.

The normal foot, when bared, and made 80 wet on the bottom or sole; and then pressed on a smooth, dry surface, will make a print of the heel, the outer portion of the middle of the underside of the foot, and the ball of the foot; together with the bottoms of 85 the toe-tips pressing downward as one moves forward. But the inner portion of the underside of the foot directly below the arch does not touch the surface at all. Therefore the weight-bearing portion of the foot 90 must be none other than that part which touches the surface mentioned and makes a mark when wet. Furthermore, when a person stands with feet parallel, toes directly 95 forward, it is very noticeable that the body's weight is felt chiefly on the outer side of the bottom of the foot; but very little on the inner side, directly below the arch. This conclusion is quite contrary to the arch-prop idea; which many have assumed to be true; 100 but without proof. Hence, a pedestrian, walking with the feet straight ahead or parallel is constantly bearing his weight on the outer portions of the bottoms or soles of his feet; so that his arches are never overstrained; but simply bear sufficient weight 105 to keep them flexible. On the other hand, the pedestrian who walks with his toes

turned outward concentrates the larger part of his weight on the inner portions of the soles of his feet, directly below the arches; and with every step forward, an inward 5 rolling action of the inner portions below the arches takes place. This results in an undue strain in the ligaments that bind the joints together. After a while, the ligaments become stretched out longer than normal; making it possible for one or more of the arch bones to project inward and out of natural position; seriously interfering with the articulation of the joints; and producing strain, pressure or impingement of one or 10 more nerves, with the pains usual in such cases. Now the "out-toeing" of shoe-wearers is largely due to the round, hard edge of shoe-heels; for the majority of pedestrians strike the back edge of the shoe-heel 15 first. Then the toe of the shoe very naturally and easily swings outward, and does not fully regain the parallel position by the time the sole of the shoe reaches the floor or pavement. A continuance of such 20 movement finally establishes the "out-toeing" habit. There is also a very unwise custom of teaching children to toe outward; and the ill effects are everywhere in evidence. My invention seeks the prevention 25 of this abnormal shifting of the foot while in the act of making a step; and I prefer to style it a "footstep corrector" for that reason. It is constructed and applied as I shall now set forth in the detailed description of 30 the drawings herein.

I employ the numeral 1 to indicate a heel for a conventional article of footwear, such as a shoe, shown in part at 2. Embedded in the heel is a bar or body 3, which is secured 35 against the lower face of the lowest but one of the lifts or layers 4. This bar 3 is preferably of rubber; though other suitable material may be employed; and it is somewhat flat and elongated in shape; comprising enlarged or widened ends 5 and 6, connected 40 by an intermediate or central portion. The extremity 5 is square or spear-headed in shape, while the extremity 6 is approximately triangular, or somewhat like the 45 quadrant of a circle. The extremity 5 is located at the inside corner at the front of the heel; and the extremity 6 is located at the rear of the heel, toward the outer side of the same. The bar or body 3, therefore, 50 extends diagonally across the bottom of the heel from the inside of the foot in front to the outer side at the back; and these extremities conform to the outline of the heel adjacent to them. The body 3 is made thick 55 enough to project somewhat from the bottom of the heel; and to this end I make the lowest lift or layer 4 thinner than the bar 3. This lowest lift comprises two sections 7 and 8, one on each side of the bar 3, and 60 65 forming along their inner edges to the sides

of the bar to give a finished appearance. In order to secure the body 3 in place, I provide holes 9, having countersunk outer ends 10 to receive washers 11. Fastening devices, such as nails 12, pass through the washers 70 11 and the holes 9, into the heel; and the heads of the nails, as shown in Fig. 3, will be above the lower surface of the bar 3 and thus be prevented from coming into contact with the ground. Preferably four nails are 75 employed; two for the extremity 6, one for the extremity 5, and one for the connecting or central portion. I also employ cement on the upper or inner face of the bar 3 to make it stick to the adjacent lift 4 and assist the 80 nails 12.

Other ways of securing the bar 3 in place may be devised. In the modification illustrated in Figs. 4 and 5, I dispense with the nails and provide the central portion 13 with ribs or flanges 14 along its sides, between the enlarged ends 5 and 6. These flanges will be pressed against the heel by the sections 7 and 8; and, in combination with cement all over the top or inner face of 90 the bar 3, will answer the purpose very well.

I shall now show the utility and value of my invention. The majority of pedestrians, as above stated, put down the back edge of the heel first; while a few shove or drag the feet along as they walk. My step corrector provides for both of these movements. If one strikes the ground or pavement first with the back outer edge of the shoe-heel, the rounded or quadrantal end 6 of the bar 100 or body 3 will stick or cling to the ground, floor, or pavement, while the leather at 8, being of a less frictional nature, permits the toe of each shoe to swing inward toward the other on the opposite foot; thereby producing the correct or parallel step. If the pedestrian shoves or drags his feet along, then the inner forward corner of the shoe-heel, where is placed the square end 5 of the bar 3, will stick or cling to the pavement; 105 and the leather at 7 now permits the toe of the shoe to swing inward toward the other; thereby producing the correct or parallel step in this case also.

The step corrector bar 3 is made from one 115 sixty-fourth to one thirty-second of an inch thicker than the leather sections 7 and 8 on either side. This greater thickness not only increases the power of the bar to stick or cling to the pavement; but also gives the additional advantage of an almost noiseless step; and the body 3 is much lighter than the ordinary solid rubber heel besides.

My invention, by correcting the out-toeing habit, thus transfers the body's weight from the arch or inner side of the sole of the foot to the outer side of the sole; thereby relieving the arches of all undue weight, and making it possible for an arch which is 120 broken down, and out of adjustment to re- 125 130

turn to its normal condition. Also the step corrector bar, being a little thicker than the layer of leather on either side, so reduces the jar in walking that it is hardly perceptible; and the bar therefore is of greater value in protecting the nervous system from destructive shocks than even the solid rubber heel; which of necessity is made of harder rubber. Again, my invention, as a means of protection against out-toeing and its resulting evils, even for those not afflicted with arch troubles, is of no small value; and a further advantage of my foot-step corrector over solid rubber heels is secured by the open spaces or recesses provided by the countersunk or enlarged outer ends of the holes 9 receiving the nailheads. These recesses produce suction on a wet pavement, and obviate the danger of the wearer slipping.

My step corrector bars 3 are of course made for right and left shoes, so as to be employed on both heels. Figs. 1 and 4 illustrate such a bar on the left heel; and Figs. 2 and 3 a bar on the right heel. The bars are both therapeutic and preventive.

The extremities 5 and 6 are the primary ground-engaging portions of my step-corrector; though of course when the wearer's whole weight is exerted on either foot, the whole bar will be pressed firmly down on the surface of the ground; whether the latter be pavement, floor, or earth. If desired, the intermediate portion between the ends 5 and 6 can be omitted. My invention is applicable to boots as well as shoes, or to any article of footwear, in fact.

I do not wish to be limited to the exact construction herein set forth; but reserve to myself the right to make such changes in the shape, size and arrangement of parts as fairly fall within the scope and spirit of my invention.

Having described my invention, what I claim as new and desire to secure and pro-

tect by Letters Patent of the United States is:—

1. The combination, with the heel of an article of footwear, of means associated with the heel and projecting below the bottom thereof for providing a ground-engaging portion at the back of the heel and to one side of the same, and another ground-engaging portion adjacent to a corner of the heel and diagonally opposite the first-named portion.

2. The combination, with the heel of an article of footwear, of means associated with the heel and projecting below the bottom thereof for providing a ground-engaging portion at the back of the heel and to one side thereof, and another ground-engaging portion adjacent to the inner corner of the heel and diagonally opposite the first-named portion.

3. The combination, with the heel of an article of footwear, of a body embedded in the heel but projecting from the bottom thereof, the body extending diagonally across the heel from the inner corner at the front to the outer edge at the rear, and having enlarged portions at its extremities.

4. The combination, with the heel of an article of footwear, of a body embedded in the heel and projecting from the bottom thereof, the body extending diagonally across the heel from the front inner corner to the outer edge at the rear, the body having enlarged portions at its extremities conforming to the outline of the heel, said body also having countersunk holes to enable it to be secured in place.

Signed at Minneapolis in the county of Hennepin and State of Minnesota this 13th day of May A. D. 1914.
